UNITED STATES PATENT OFFICE

HOWARD W. EARNSHAW, OF COLUMBUS, OHIO, ASSIGNOR TO THE LILLEY COMPANY,
OF COLUMBUS, OHIO, A CORPORATION OF OHIO

TOOL-HANDLE CONSTRUCTION

Application filed December 30, 1926. Serial No. 158,111.

This invention relates to an improved handle construction adapted especially for use in connection with swords and other bladed instruments, and has for a primary object the provision of a handle structure which may be quickly, securely and positively connected with the handle shank of an instrument blade to the end that the handle structure will be rigidly secured in a non-rotatable manner and a strong and economical construction provided.

Another object of the invention resides in the provision of a handle structure of the character set forth wherein the tool or instrument blade is provided with a handle shank of outwardly tapering form and of substantially rectangular formation in cross-section, and wherein the handle body is provided with an axially disposed bore or passageway in which the tool shank is received, the said bore or passageway being somewhat smaller in diameter than the tool shank, in order that when the handle body is applied to the tool shank it will have to be forced or pressed thereon in such manner that the corner edges of the tool shank will cut or bite into the walls of the bore or passageway to a limited extent, thereby enabling the handle body to be rigidly and non-rotatably mounted in connection with the instrument or blade with which it is associated.

For a further understanding of the invention reference is to be had to the following description and the accompanying drawing, wherein:

Figure 1 is a vertical longitudinal sectional view taken through the handle construction of a sword and illustrating the features of the present invention.

Figure 2 is a similar view taken through the handle construction on a plane at right angles to that shown in Figure 1,

Figure 3 is a detail cross-sectional view on the line 3-3 of Figure 1,

Figure 4 is a similar view on the line 4-4 of Figure 1.

Referring more particularly to the drawings the letter A indicates the blade of a sword, the letter B the hilt of the sword and the letter C the handle construction thereof.

While the features of the present invention are applicable to instruments and tools other than swords the latter will be employed hereinafter merely for convenience in specifically defining the invention, although it is to be understood that the invention has much wider application and where possible invention shall be construed to cover all of the various uses to which it may be placed.

In this instance, however, the blade A terminates in a shoulder 1 and then in an upwardly longitudinally extending, tapering shank 2. The shank is of substantially rectangular form in cross-section, as shown in Figures 3 and 4, and for reasons to be hereinafter explained. The hilt B or other cross member is formed with an axial opening for the reception of the lower or widest portion of the shank and rests upon the shoulder 1, the hub 3 of said hilt serving as a base against which rests the inner ferrule 4 of the handle structure C. The handle structure comprises a body 5 having the customary external form, but is formed to include an inwardly and axially extending bore or passageway 6, which tapers in conformity with the taper of the shank 2. By reference to Figure 4 it will be observed that the diameter of the bore or passageway 6 is slightly less than the diameter of the shank while the latter is measured between obliquely disposed corners. Since the body 5 is formed from a yieldable material, such as wood, composition, fiber, bakelite or the like, it will be seen that when the handle body is driven downwardly upon the shank, the corners of the latter, indicated at 7 will bite into the walls of the bore or passageway 6 so as to effect a secure union between the handle body and the shank. This produces a construction of strong and durable form, and wherein the handle body will be non-rotatably mounted on the tool shank, preventing the undue loosening of the handle body, rattle and rotation thereof as is frequently encountered in constructions of ordinary form.

The handle body is provided at its upper end with an outer ferrule 8 which also is provided with a tapering axial opening 9 for the reception of the outer end of the shank. 100

The opening 9, as is the bore or passageway 6, is formed so that the corner edges of the ferrule will penetrate the walls, as is disclosed in Figure 3, to prevent the rotation of said ferrule. If desired, a cross pin 10 may extend transversely through registering openings provided in the ferrule 8 and the shank 2, so as to positively lock the handle construction in its applied position upon the shank, and to prevent the handle construction from being accidentally slipped off or removed from the tool shank.

In view of the foregoing it will be seen that the present invention provides a simple and positive handle construction for swords and other manually wielded instruments. The construction has the advantage of being economical from a manufacturing standpoint and at the same time positive and efficient in operation.

What is claimed is:

In a tool, a blade provided at one end with a longitudinally extending outwardly tapering shank, said shank being rectangular in cross-section and having a uniform thickness throughout its length, and a handle body for the reception of said shank formed with a tapering bore of oblong formation with its shortest diameter uniform throughout its length, said bore possessing a diameter so that the corners defined by the meeting edges of the walls of said shank will penetrate to a limited extent into the material defining the walls of said bore.

In testimony whereof I affix my signature.
HOWARD W. EARNSHAW.
